FRITZ TRACHSEL, OF BERNE, SWITZERLAND, ASSIGNOR TO CHR. GEELLER AKTIEN-
GESELLSCHAFT, OF BERN-BUMPLIZ, SWITZERLAND

AUTOMATIC TELEPHONE EXCHANGE SYSTEM

Application filed April 12, 1926, Serial No. 101,516, and in Switzerland April 15, 1925.

- This invention relates to automatic telephone exchange systems and provides an improved construction or arrangement of a pilot switch used in such systems comprising selecting devices located in the exchange and adapted to operate automatically under the control of interrupters or "selector discs" which form part of the subscribers' sets and which are operated by the calling subscribers.
- According to the invention the exchange comprises a number of similar switching devices (one for each subscriber) adapted to be operated selectively by an operating member having a step-by-step movement and so arranged and connected that the switching devices of the calling and called subscribers are first moved into a position of readiness under the control of the calling subscriber's set and are then operated automatically by the movement of the operating device so as to effect the requisite connections between the called and the calling subscribers.
- In order that the invention may be more readily understood reference will now be made to the accompanying drawings in which:—

- Fig. 1 is an elevation showing the arrangement of a bank of switching devices,
Fig. 2 is an end elevation in which only one magnet M39 is shown,
Fig. 3 is a partial top plan view of one of the switching devices,
Figs. 4, 5, and 6 are enlarged detail views,
Fig. 7 is an enlarged detail view of one of the rods or blades St,
Fig. 8 is a diagram of the parts used in a single pilot switch.

- As shown in the drawings the exchange comprises a number of mechanical switching devices (one for each subscriber) arranged one above the other and each comprising two horizontal sliding rods, Zu' and Zu², Fig. 3, adapted to operate a number of sets of spring contacts.
- The spring contacts are arranged in vertical rows mounted on insulated supports m. For each subscriber there is provided one set of contacts p operated by a cranked end e of the rod Zu², one set of contacts w operated by one end of the rod Zu' and several sets

of contacts du which are operated by projections z provided on strips or tongues He', He², attached to spring strips f fixed on the supports m.

As shown in Figures 2 and 4 each set of contacts du comprises eight spring strips constituting four contact points which are arranged in pairs on either side of the rod Zu', the contact points above the rod Zu', Fig. 2, being operated by the tongue He² whilst the contact points below the rod are operated by the tongue He'. For each pair of tongues He' and He² there is provided on the rod Zu' a collar or abutment Mi' adapted to engage and move the tongues He' and He² as hereinafter described. The rod Zu² is provided with similar collars or abutments Mi² adapted to be engaged and moved by the tongues He', He² to move the rod Zu² in a direction to open the contacts p.

The rod Zu' is provided with an armature An controlled by an electro-magnet M which is adapted to move the rod against the action of the spring strips f from the position shown in Figure 3 towards the position for closing the contacts du.

For each set of contacts du provided for one subscriber there is a vertical sliding rod St', St², or St³ in the form of a flat strip having lateral projections No struck out from the strip adjacent one edge and adapted to engage the free ends of the strips He', He². In the normal position of the strips He', He² shown in Fig. 3 the free ends thereof are clear of the path of movement of the projections No but when

any of the rods Zu' is moved by its magnet M towards the position for closing the contacts du the free ends of the corresponding strips He', He² are moved into the path of movement of the projections No so that by the vertical sliding movement of one of the rods St', St², St³ one of the strips He', He² provided for the selected subscriber can be engaged and moved by one of the projections No so as to effect closure of the corresponding contacts du. The strip He' or He² also moves the rod Zu² by engaging one of the abutments Mi² so as to break the contact between the spring contacts p. The parts are so proportioned that although the magnet M is capable of

moving the rod Zu' against the action of the springs trips f sufficiently to close the contacts w , none of the contacts du or p , are affected until one of the strips He' , He^2 is engaged and moved by a projection $No.$ The position of a strip He^2 after being moved by a projection $No.$ is shown in dotted lines in Fig. 6 of the drawings.

Each of the vertical rods St' , St^2 , St^3 is adapted to be moved from its lowermost to its uppermost position step by step by means of a pawl Kli' adapted to engage ratchet teeth provided on the rod and controlled by an electro-magnet H and armature Ak and so arranged that when the electro-magnet H is de-energized the pawl Kli' is out of engagement with the ratchet teeth on the rod as shown in Fig. 2. Downward movement of the rod during the intervals between successive operations of the pawl Kli' is normally prevented by means of a pawl Kli^2 controlled by a spring Fe which is capable of moving the pawl into two positions of equilibrium in one of which it tends to engage ratchet teeth formed on the rod as shown in Fig. 2, whilst in the other position it is out of contact with the rod. Two stops q' , q^2 are fixed on the lower end of the rod and are adapted to act on a lever or projection fixed to the pawl Kli^2 , as shown in Figure 2 so that when the rod reaches its uppermost position the projection q' moves the pawl Kli^2 out of engagement with the rod and permits the latter to fall by gravity into its lowermost position and to act upon the pawl Kli^2 by means of a strip q^2 so as to restore the pawl Kli^2 to the position shown in Figure 2.

Each of the rods St' , St^2 , St^3 has contact arms or brushes Kfd co-operating with rows 40 of contacts Kdg and constituting a pilot switch. This pilot switch is only diagrammatically indicated in Figures 1 and 2 of the drawings but is more completely shown in Figure 8. It comprises four contact arms I, II, III, IV, each of which co-operates with a separate row of contacts. The contact arms I, II, III, IV, move together in the example shown in the drawings through fourteen successive positions corresponding to fourteen successive positions provided for by the pawls Kli' , Kli^2 and their ratchet teeth. In each of these positions, each of the contact arms I, II, III, IV bridges two adjacent contacts, certain of which are numbered in Figure 8.

While Figure 1 shows a plurality of the pilot switch mechanisms used in this invention, assembled side by side to constitute an exchange system, it will be understood that this duplication of the switch elements is 55 simply to provide simultaneous service to a number of subscribers. The invention claimed in this application relates more particularly to the design and construction of any one pilot switch, adapted to selectively operate under the control of a subscriber's

"selector disc", common to all such systems, to effect a selective control of speaking circuits connecting two stations.

Generally speaking, the operation of any one of the pilot switches may be described as follows:

When a calling subscriber lifts his telephone, one of the magnets M , say M^{30} , Figure 3, is energized. This causes armature An^{30} to move rod Zu' a certain distance sufficient to set one of the tongues He' , or He^2 , sideways and cause it to be mechanically engaged by the cam projection No on the appropriate selector rod St' etc. This initial movement of the rod Zu' is only sufficient in extent to close contact w , which effects a connection with the calling subscriber's line, all contacts du remain open and contact p remains closed. Further movement of rod Zu' can only be effected by manipulating the selector rod St' , used with that subscriber and moved by his selector disc through the agency of a magnet H , the detailed operation of which has been described above.

This further movement of rod Zu' takes place because of the engagement of one of the projections No with one of the tongues He' , or He^2 , the up and down movement of the selector bar, carrying the projection No , causing the latter to impart a sideways thrust to rod Zu' which closes one of the du contacts and opens contact p , the effect of opening the last named contact being to isolate that particular selector, or pilot switch from calling operation. It will thus be seen that each switch element initially can be energized by a calling subscriber to automatically effect a selective line connection with the called subscriber.

Summarizing certain essential features disclosed by the pilot switch of this invention, it will be found that the contact p , Fig. 3, provides an element designed to impress on the switch mechanism an initial selective setting of the switch parts which places it in communication with the line of the subscriber called, through contact w . After this stage of the switch operations, the selector bar appropriate to the desired subscriber is brought into play to effect a further selective setting among the contacts du , which will be determined by his call number, the completion of this operation will result in a speaking connection having been made automatically by the switch. In practice, it will be understood that both subscribers will be provided with at least one of the pilot switches described.

What I claim is:

1. In a switch for an automatic telephone exchange, a plurality of spring contacts placed side by side, cams mounted adjacent said spring contacts, means adapted to effect a successive plural stage movement of said cams, comprising a slide bar under magnetic

control, in combination with a plurality of magnetically controlled bars operating transversely to said slide bar to selectively effect a final movement of one of said cams

5 with respect to an associated spring contact.

2. In a telephone exchange switch mechanism, a series of spring contacts placed side by side, a cam associated with said contacts in combination with an operating slide bar under magnetic control designed to move said cam to a selective position, and a plurality of other bars transversely movable with respect to said slide bar by magnetic means, one of which is designed to engage said cam and move it from selective position to contact closure position of its associated spring contact.

10 3. In a telephone exchange switch mechanism, a series of spring contacts placed side by side, a cam for closing said contacts, in combination with a slide bar under magnetic control designed to set said cam to a preliminary closure position, other bars, magnetically operable at right angles to said slide bar and provided with means to selectively engage said cam when placed in said preliminary closure position, and a second slide bar movable parallel to said first slide bar under the selective control of said cam to open one

15 30 of said spring contacts.

4. In an automatic telephone switch, a series of spring contacts placed side by side in combination with a plurality of parallel slide rods each provided with selectively spaced tappets, and means for causing said tappets to close and open certain of said spring contacts through a step by step movement of said rods.

In testimony whereof I affix my signature.

40 FRITZ TRACHSEL.
